UNITED STATES PATENT OFFICE

2,673,534

SUPPORT FOR REFRACTORY LINED FURNACE DOORS OR THE LIKE

George L. Robinson, Pittsburgh, Pa., assignor to
 Blaw-Knox Company, Pittsburgh, Pa., a corporation of Delaware

Application January 18, 1951, Serial No. 206,630

6 Claims. (Cl. 110—173)

1

This invention relates to replaceable and detachable supports, that is, anchor members for refractory lined furnace doors or the like. More particularly, it pertains to a retaining member and replaceable or detachable anchor stud combination for the plastic refractory lining and peephole ring respectively of furnace doors such as those used on open-hearth furnaces. Reference is hereby made to my copending United States patent application Serial No. 118,336 filed September 28, 1949.

It is customary to line water-cooled furnace doors with a plastic refractory cast in the hollow recess of the door, and to secure the lining to the door by means of metal studs projecting from the face of the door and embedded in the refractory, the studs being secured to the face of the door by some means. The refractory lining and the studs are consumed or eroded away by action of the hot furnace gases, and require replacement after about one to three months of service. The furnace door itself may last about four to five years before it must be replaced. A typical steel mill may have about ten to twelve furnaces, each with five doors. If these doors require relining at about six weeks intervals, it is evident that about nine or ten of these doors may have to be relined each week. It is apparent, therefore, that a new construction and manner of fastening anchor studs which increases the ease and economy of re-studding and re-lining a furnace door is important.

Various means for securing such studs to the door have been suggested and used. Assuming such studs have the same material and spacing, they are believed to give comparable performance during the time the door is on the furnace. However, they are not as satisfactory as the replaceable supports of this invention insofar as ease and cost of replacement are concerned. Thus, the most common practice is to weld one end of the stud to the face of the recess in the door. When such a door is to be relined the residual ends of the consumed studs must be burned or clipped off at the door face. Such preparation for the welding on of new studs, as well as the welding itself, is expensive. Other fastenings for studs, not requiring welding, have also been suggested. Some of these involve holding a rearward extension of the stud in the hollow water-cooled body of the door, and are not only relatively high in cost but impose restrictions on the door construction to accommodate the desired stud spacing. Others, such as nuts permanently welded to the face of the door into which

2

studs with threaded ends are screwed, have proved impractical due to the difficulty of removing the stub-end of the burned-down stud from the nut. None of the prior devices has been wholly satisfactory and some better solution to the problem has long been desired.

Similarly, a problem has arisen relative to the fastening of the peephole extensions within the refractory lining space of furnace doors such as those for open-hearth furnaces. These peephole extensions are frequently in the form of pipe sections arranged in coaxial registry with the peephole ring through the hollow water-cooled body of the door. They thereby protect the edge of the refractory around the peephole itself particularly when taking samples through the peephole and, with plastic refractory linings, serve as a casting form during the casting of the lining. A common method of fastening the peephole extension has been to weld it to the furnace door at the back of the lining recess thereby making it a part of the structure of the door. In service the peephole extension will burn away in part at least. Hence, when the door is relined, replacement of the peephole extension is usual. For this, it is necessary for the furnace door to be sent to the mechanical department so that the old extension ring can be removed as by chipping out the weld thereof to the door and then the door is sent to the welding department where a new peephole extension is welded in place. As a consequence, the water-tight integrity of the body of the door may be impaired and, in any event, the door remains out of service for a relatively considerable period of time and involves the expense of handling and treatment which has been outlined by skilled workmen.

The instant invention overcomes the foregoing difficulties in that the retaining members are permanent and trouble-free and the anchor members are readily detachable and replaceable despite any bending or movement in the structure of the door which may occur in operation. Further, the retaining and anchoring members which are made in accordance with this invention are readily applied to a wide variety of furnace doors; involve no larger repair problem when the relining or peephole replacement thereof is in order; and permit the same unskilled workmen, who are to renew the lining, to replace the burned studs and such peephole extension quickly and effectively before the new lining is cast.

Other objects and advantages of this invention will be apparent from the following description

3

and the drawings, which are illustrative only, in which

Figure 15 is a view in elevation of the modified embodiment shown in Figure 14 taken along the line XV—XV of Figure 14.

The preferred embodiment of this invention applied to the supports for a plastic refractory lining and illustrated in enlarged view in Figures 4 to 6 inclusive is shown on the furnace door in Figures 1 to 3 inclusive. This furnace door is the subject of United States patent application Serial No. 613,073 filed August 28, 1945 in the name of Edward W. Pottmeyer, now Patent No. 2,547,229 dated April 3, 1951. Although the door of the said application Serial No. 613,073 is particularly useful in the practice of the instant invention, the instant invention may also readily be used with both solid and full panel type furnace doors.

In Figures 1 to 3, such a furnace door 10 has an inner wall 11, the inner side 12 of which comprises the face of the door against which a refractory lining 13 is periodically cast as each relining is performed. A hollow peripheral flange 14 extends around the outside of the door 10. These flanges have inner sides 15 set at a slight angle to each other to form a dovetail fit with plastic lining 13. Wall 11 also has a rear or outer surface 16 against which water-cooling means are applied. These water-cooling means comprise a series of vertical channels 17 which

intercommunicate with each other and with vertical flanges 14a through the horizontal flanges 14b of the hollow peripheral flange. Pipe nipples 18 welded to the top of door 10 respectively form an inlet and an outlet to the cooling water passages through door 10. Washout plugs 20 are threaded into tapped holes in blocks 21, which tapped holes communicate with the cooling water passages in door 10 at the bottom of the vertical rails 14a of flange 14. A lifting yoke 22 and lugs 23 for conventional counterbalance cables afford a conventional arrangement for the raising and lowering of door 10.

Peephole 24 and peephole extension 25 are metal ring sections in registry and together form an observation port through door 10 including the central channel 17. A wearing plate 24a may be welded around the inside lower portion of peephole ring 24. A cover 26 normally rests against ring 24 and closes the port. Cover 26 is operated by means of a chain 27 in a conventional manner.

In the preferred embodiment of a plurality of retaining members or clips 30 is welded in a pre-determined pattern to surface 12. This pattern may be varied so long as it furnishes the required support for a plastic refractory lining to be cast against surface 12 and the respective inner sides 15. Each retaining member 30 is in the form of a retaining member or socket of a material like sheet steel bent into the form of a longitudinal arch having a longitudinal central portion 31 spaced away from surface 12. This spacing is obtained by the divergence of two side portions 32 extending toward surface 12 so that the innermost side edges thereof may be welded to metal wall 11. A U-shaped recess 33 is cut or punched through central portion 31 for a substantial portion of the length thereof downwardly from the top edge 34 of retaining member 30. Since central portion 31 and sides 32 are each relatively plane, the space between recess 33 and the lower part of portion 31 and surface 12 is relatively trapezoidal in configuration.

As a consequence, an anchoring member such as a stud 35 of steel, copper or other suitable metal having an outwardly flared or countersunk base 36 of greater diameter than the width of recess 33, can be held tightly against surface 12 by sliding it with body 36a substantially between recess 33 and surface 12. The base 36 of stud 35 is of a diameter which readily passes through recess 33 between the sides thereof so that it extends normal to wall 11 into the space to be occupied by a lining 13. In practice, stud 35 is a rivet with a countersunk head, which head acts as base 36. In the formation as by bending of socket 30, the slope of sides 32 is generally similar to the flaring of the sides of base 36. Thus, as shown in Figure 6, the inner edge 37 normally bears against base 36 to insure a proper fit between stud 35 and socket clip 30.

Because of the arch shape of retaining member 30, it is open at the top and at the bottom as shown in Figure 5. Any refractory or other material which may accumulate around base 36 within socket 30 during use is readily removable either when the stub end of stud 35 is removed or thereafter. Such stub ends can readily be removed by knocking them up by hammer blows and out of their respective sockets 30. Any other material between sockets 30 and wall 11 can be dislodged by further blows or by poking the material out with a chisel. Thereafter, new studs

35 may be knocked into place by moving them downwardly in recess 33 generally parallel to wall 11. Although the rearmost portion of the sockets 30 is illustrated as surface 12, such sockets may, if desired, be provided with back plates of their own which back plates can then be welded to wall 11 to form the combination of this invention. Further, although the recesses 33 are illustrated as being U-shaped in vertical position, various departures from such shape and orientation may be made in particular cases.

It is evident that socket blanks which may be steel or other suitable metal can be stamped out or otherwise cut and recessed and bent very quickly and inexpensively. Such sockets would then be welded in a predetermined pattern to the particular furnace door to be used. In the case of full panel type doors using box-type panels with vertical spaces between or in the event there are observation openings for the refractory lining through the back of the door and through a wall portion corresponding to wall 11, suitable blanking off pieces can be used to fill such spaces during the casting operation while the refractory lining is still plastic. Subsequently, such blanking off pieces may readily be removed. In using a furnace door of the type illustrated in the aforesaid application Serial No. 613,073, the pattern for the sockets 30 need not make any allowance for the immediate presence of water cooling means directly in back of the respective socket on the other side of wall 11. Thus, as shown in Figure 3, sockets 30 may be directly in front of a channel 17 or directly in front of the space between adjacent such channels or directly in front of the flange of a channel affixed to surface 16.

As the lining 13 is consumed or eroded away, the studs 35 also progressively burn away. However, the studs are not completely consumed since a short stub end will remain even though the lining around it is completely consumed. It has been found in tests of the improved stud and fastening of this invention that no fusing of such stub end to its anchor socket, such as socket 30, occurs on such exposure although the exposure may be prolonged for a substantial period of time. And despite such exposure, the stub end is still easily removable and the socket remains in good condition indefinitely for the reception of new studs when the door is to be relined. Such severe exposure is not usual because furnace doors are usually relined before metal plate 11 is exposed, but it occasionally occurs. Thus, it is a further important advantage of this invention that the time of relining is not critical in relation to the functioning of the device of this invention.

When such a door is to be relined, an unskilled workman can readily hammer the old studs 35 out of the sockets 30 and similarly dislodge any hardened refractory or other material which may have collected around base 36 in socket 30. Such dislodgment is facilitated by the open bottom of socket 30 permitting the material to fall free where it can be swept away. The insertion of new studs 35 is then readily accomplished by sliding them into place with the aid of such hammer blows as may be required. A rigid pattern of new anchor members is thus quickly obtained for the new lining which can then be cast.

In Figures 7 to 9 inclusive, a modified retaining member 40 is shown, which is adapted to be welded to the face of the door along each side and its bottom edge as well, which is conical in form. A recess 41 is provided between the slop-

ing sides and conical bottom of the retaining member 40, which recess accommodates a stud 42 which is identical with stud 35. The rearwardly extending edge of retaining member 40 is welded to a wall surface such as wall 11 and functions substantially as the previously described retaining member 30 functions except that socket 40 has no bottom opening for the convenient dislodgment of caked or accumulated material. However, it has the added advantage of better distribution of the welded connection for conduction of heat to the wall 11.

In like manner to the provision of retaining and supporting members for anchoring and cooling the plastic refractory lining of furnace door 10, anchor members or studs 43 like studs 35 and 42 may be provided for the peephole extension 25. These studs 43 may be in the form of rivets having countersunk bases 44 welded around the outer periphery of peephole extension 25 with the shank or body 45 of the said studs 43 extending axially relative thereto. By these means the countersunk bases 44 face surface 12 with the relatively flat ends of bases 44 substantially in a plane parallel to said surface 12 when ring 25 is in position for attachment to or detachment from inner wall 11. When so attached the flat ends of studs 43 will normally be against surface 12 placing studs 43 and ring 25 in heat-conducting relation to wall 11 for the cooling of said studs 43 and ring 25. If three studs 43 are provided, spaced equidistant around the outer periphery of peephole extension 25, three correspondingly spaced retaining members 46 are then also provided. These retaining members 46 may be substantially identical in character and functioning to retaining members 30 and are similarly welded to surface 12 as shown in Figure 11. Hence, if a bar 47 is inserted through the openings 48 provided therefor on opposite sides of ring 25 as shown in Figure 10, the peephole extension 25 may be attached to the furnace door by rotating it clockwise as shown in said Figure 10, from the dash and double-dot position of bar 47 to the dash and single-dot position thereof. Conversely, rotation in a counterclockwise direction as viewed in Figure 10 will detach the studs 43 from their respective retaining members 46. The bar 47 is removed after each new peephole extension is connected to door 10. As in the case of the anchor members 35 and their respective retaining sockets 30, it is desirable to have a reasonably good fit between the studs 43 and the sockets 46. In such a fit, the flared end of the heads 44 will preferably bear against the surface 12 and either the flaring sides of the heads 44 or the body 45 of the studs 43 will be engaged by the edges 49 defining the recess in the respective sockets 46. In general, it is only necessary to move the studs 43 sufficiently far into said recesses to obtain the fastening engagement that is desired.

It will be noted that peephole 24 may be provided with an inner edge 24b which overlaps the outer edge of peephole extension 25 without being in any frictional contact therewith. Thereby, the attachment, detachment and replacement of peephole extensions, such as extension 25, are facilitated while at the same time serving as lining forms around the peephole extending through rings 24 and 25 for the plastic refractory during the casting thereof in the initial lining or relining of the door 10.

The modification illustrated in Figures 12 and 13 is similar in character and functioning to the

embodiment shown respectively in Figures 10 and 11 except that a flared or conical peephole extension 25' is employed. The same reference numerals are applied to the corresponding parts of the modification in Figures 12 and 13 with the addition, however, of primes as are applied to the embodiment shown in Figures 10 and 11. It will be evident that as in the case of the studs 35 and 42, different forms of enlarged bases and different forms of bodies may be employed for anchor members 43, and similarly for retaining members 46. For example, an equivalent retaining member might be made in two parts in spaced relation to achieve a socket of the character disclosed herein. A peephole extension may also be provided in the support combination of this invention, as shown in Figures 14 and 15, whereby instead of being rotated into attached or detached position, it may be translated or moved in a linear direction into attached or detached position. In such a case, all of the recesses, for example, in the retaining members 46 might extend parallel to each other and with their open ends all facing in the same direction, so that a rectilinear movement of the stud bases, such as bases 44, would fasten such peephole extension to the furnace door. In this last-mentioned arrangement, the ring corresponding to 24 would not be provided with any overlapping edge 24b but would terminate substantially in the plane of inner wall 11. Parts in Figures 14 and 15 similar in character and functioning to the other embodiments are provided with the same reference numerals with a double prime factor added thereto.

Various other modifications may be made which are within the spirit of this invention and the scope of the appended claims.

I claim:

1. In a furnace door, in combination, a wall having a surface against which refractory is placed and a peephole through said wall, a retaining member fastened to said surface of said wall adjacent the edge of said peephole, said retaining member having a recess and a space between said recess and said surface, said recess and space having an entry end and extending generally parallel to said surface, said recess and space further being in communication with one another, an anchor member having an enlarged portion generally of greater dimension than said recess and generally of lesser dimension than said space, said anchor member further having a portion of lesser dimension than said recess, and a peephole extension tubular member connected to said last-mentioned portion of said anchor member, said anchor member having its portion of lesser dimension extending in a direction axially of said tubular member and being adapted to have its portion generally other than said enlarged portion moved into said recessed portion through said entry end to fasten said enlarged portion substantially in the space between said retaining member adjacent its said recessed portion and said wall, whereby said anchor member and peephole extension tubular member are fastened to said door.

2. In a furnace door adapted to be lined periodically with a refractory, in combination, an inner metal wall having a surface against which refractory is placed and a peephole extending through said wall, a plurality of retaining members attached to said surface of said wall around the edge of said peephole, each of said retaining members having a recess extending generally par-

allel to said wall and a space between said recess and said surface, said recess and space having an open end and said recess being spaced from but generally close to said surface of said wall, 5 said recess and space further being in communication with one another, a plurality of anchor members each having an enlarged portion generally of greater dimension than said recess and generally of lesser dimension than said space, 10 each of said anchor members further having a body of lesser dimension than said recess, each of said anchor members being adapted to have its portion generally other than said enlarged portion moved into said respective recess and 15 space portions through said open end in a direction generally parallel to said wall, said enlarged portion being fastened substantially in the space between its respective retaining members adjacent its said recess and said wall, and a 20 peephole extension tubular member connected to said body of said anchor members, said body between said peephole extension tubular member and said enlarged portion of said anchor members extending in a direction axially of said tubular member, whereby said anchor members and peephole extension tubular member are detachably fastened by said retaining members to said door.

3. In a furnace door to be refractory lined 30 having a peephole, in combination, a wall having a metal surface against which said refractory is placed and through which said peephole extends, a plurality of sockets each welded to said wall at said surface and around the edge of said peephole, said sockets each having a central portion spaced from said surface, said central portion having a narrower recess extending inwardly from a corresponding edge of said sockets and substantially parallel to said surface, said sockets 35 each defining a space between said recess and said surface with said recess in communication with said space, a plurality of studs each having an enlarged base and a portion connected thereto which is narrower than said recess, said enlarged 40 base being of greater dimension than said recess but of similar lesser dimension than the space between said central portion and said wall when the portion of said stud generally other than said enlarged base is slid into its respective recess with the axis of said stud substantially normal to said surface, and a peephole extension tubular member connected to said last-mentioned portion of said studs.

4. In a furnace door adapted to be lined periodically with a refractory, in combination, a wall having a substantially continuous metal surface against which said refractory is placed and a peephole through said wall, a plurality of sockets attached to said wall in a predetermined pattern around the edge of said peephole, said sockets having generally U-shaped recesses therein extending generally parallel to said wall, said recesses being smaller than the area covered by the perimeter of said sockets at said surface to 60 provide a space between said recesses and said wall widening toward said wall, each of said recesses and its respective space being in communication with one another, said recesses generally facing in the same direction on a circle circumscribed about the center of said peephole, 65 a plurality of studs each having a flared base larger than said recesses, said flared base being generally similar in cross section to but somewhat smaller than the space between said recesses and 70 said wall, said studs further having shanks of a

size which will extend through said recesses, and a peephole extension tubular member connected around its periphery to said shanks of said studs, each of said shanks between said peephole extension tubular member and its flared base of said studs extending in a direction axially of said tubular member, whereby said studs may be fitted into said sockets by engagement of said bases respectively between said recesses and said wall when said peephole extension tubular member is rotated.

5. In a furnace door to be refractory lined, in combination, an inner wall through which a peephole extends, said wall having a surface against which refractory is placed, a plurality of open-ended recessed sockets permanently fastened to said surface of said inner wall in similar spaced relation around the edge of said peephole, said sockets having their respective recesses parallel to and spaced from said inner wall and extending inwardly from one edge thereof, each of said sockets defining a space in communication with said socket recesses, said space being between said socket recess and said surface, a plurality of studs each having a flared base and a smaller body, said flared base having a dimension greater than said recess but less than the space between said recess and said surface so as to fit and be retained by its respective said socket with the body of said stud extending through said recess in said socket generally normal to said inner wall, the aforesaid edges of said sockets facing in a direction such that one continued movement will engage said flared bases generally between said sockets adjacent said recesses and said wall, said body having a size which will pass through its respective recess, and a removable peephole extension tubular member coaxial with said peephole and rigidly connected to the respective bodies of said studs in an axial direction around the periphery of said peephole extension tubular member, the peripheral spacing of said studs being substantially equal to the respective spacing of said sockets.

6. In a furnace door to be refractory lined, in combination, an inner wall having a peephole 45

therethrough, said wall having a surface against which refractory is placed, a removable peephole extension tubular member having a diameter at least as large as the diameter of said peephole, 5 axially extending anchor members each having a body welded to the outer periphery of said peephole extension tubular member, said anchor members being angularly spaced from each other and having an enlarged base extending beyond said 10 peephole extension tubular member toward said inner wall, said enlarged bases respectively having flat ends generally lying within a single plane, retaining members equal in number to said anchor members connected to said surface of 15 said inner wall and spaced around said peephole corresponding to the spacing of said anchor members, said retaining members having recesses spaced from said inner wall and extending inwardly from one edge of said respective retaining 20 members in a direction parallel to said wall, each of said retaining members defining a space in communication with said recess, said space being between said recess and said surface, said recesses lying on a circle circumscribed about 25 the axis of said peephole extension tubular member and facing in the same circumferential direction, said bases having a dimension larger than said recesses but generally similar to and somewhat smaller than the space between said 30 recesses and said surface, said bodies having a dimension smaller than said recesses, whereby when said peephole extension tubular member is rotated about its axis, it may be attached to or detached from said furnace door with said flat 35 ends substantially against said inner wall.
